A. OFSTEDAHL

HALTER FASTENER

Filed May 22, 1924

Patented July 14, 1925.

1,546,306

UNITED STATES PATENT OFFICE.

ANDREW OFSTEDAHL, OF SCOUT LAKE, SASKATCHEWAN, CANADA.

HALTER FASTENER.

Application filed May 22, 1924. Serial No. 715,178.

To all whom it may concern:

Be it known that I, ANDREW OFSTEDAHL, a subject of the King of Great Britain, residing at Scout Lake, in the Province of 5 Saskatchewan and Dominion of Canada, have invented certain new and useful Improvements in Halter Fasteners, of which the following is a specification.

My said invention relates to a halter fastener for use particularly in mangers or horse stalls but adapted to be used also in other analogous situations where it is desired to quickly attach or detach a rope or other restraining device.

15 It is an object of the invention to provide a device which may be applied to a wooden bar or the like, and which may be readily used to grip a halter rope or the like firmly and which may be readily operated to release said rope thus avoiding the necessity of tying a knot which would necessarily have to be untied to be removed.

The invention will first be hereinafter more particularly described with reference 25 to the accompanying drawings, which are to be taken as a part of the invention, and later pointed out in the claims at the end of the description.

In said drawings:

30 Fig. 1 is a perspective view of a bar with the halter fastener applied thereto;

Fig. 2 is a side elevation of the fastener with parts broken away; and

Fig. 3 is a side elevation of a modified 35 form.

In said drawings, in which the same reference characters are used to denote corresponding parts throughout the several views, the invention comprises a body member 10 formed preferably of a sheet of metal bent to fit about a bar 11 of a substantial size such as is used in stalls for horses. The body member 10 is adapted to be secured to the bar by means of nails driven through 40 each side adjacent the end thereof, as shown, and has the central portion which is adapted to fit over the edge of the bar provided with a cut away portion, at one end of which is hinged a latch 12 formed with an inclined 45 forwardly extending tongue 13 adapted for engagement with a catch 14 to secure the latch in a closed position. The body member 10 is further provided with side portions 50 extending substantially at right angles to its body portion, and having triangular notches 16, one at each side of the

latch member adapted for cooperation with notches 17 similarly located in the latch 12. The apices and sides of the triangular notches are preferably rounded to prevent 55 injury to a rope. As shown the catch 14 is formed integrally with the body member 10 from that portion of the body member which is cut away and is sufficiently resilient to be sprung to permit the tongue 13 of the latch to be released, however, obviously the catch might be formed separately of spring metal and be secured in the proper position for engaging the latch tongue 13. As shown in Fig. 2 the bar 11 has cut away portions 60 65 or notches 18 and 19 which serve respectively to accommodate the latching means and the fastening means for the halter. The notches 18 and 19 extend transversely across the bar 2 and the notch 19 is adapted to receive a 70 rope or halter 20 having a knot tied in one end to prevent the rope slipping through the notch. To facilitate manipulation of the latch 12, a handle 12' may be provided, which in the present instance, is shown as 75 an iron rod having each end inserted through the body of the latch and expanded to prevent removal.

In the modification shown in Fig. 3 a 80 latch 21 is provided having side portions bent at substantially right angles to the body portion thereof and with triangular notches, one on each side thereof, adapted for cooperation with a transverse notch 22 in a bar 23 to which the device is secured. 85 The latch 21 is hinged to a metal securing member 24 which may be fastened to the bar 23 by screws or any other preferred means. This latch is adapted to be swung on its hinge into engagement with the bar to 90 clamp a rope between the notch in the bar and the notches in the side portions of the latch. To secure the latch in position I provide a pin 25 adapted to extend transversely through the outer end of the latch 95 and through the bar.

It will be obvious to those skilled in the art, that various modifications may be made in my device without departing from the spirit of the invention and therefore I do not limit myself to what is shown in the drawings and described in the specification, but only as indicated in the appended claims.

Having thus described my invention what 110 I claim as new and desire to secure by Letters Patent is:

1. A halter fastener comprising a body member having an intermediate face and side faces extending therefrom, said intermediate face having an opening of a width equal to the width of said face, registering notches in said side faces, a latch pivoted to said body member having notches adapted to be brought into position to clamp a halter in the notches of the body member, substantially as set forth.

2. A halter fastener comprising a body member having an intermediate face and side faces extending therefrom, said intermediate face having an opening of a width equal to the width of said face, registering notches in said side faces, a latch pivoted to said body member having notches adapted to be brought into position to clamp a halter in the notches of the body member, and means for securing said body member on a support, substantially as set forth.

3. A halter fastener comprising a bar having a notch in its face, a body member shaped to fit over the bar and having an opening over said notch, a latch pivoted at one end of said opening, opposed notches in said latch and said body member, said latch being adapted to be swung into engagement with said body member to clamp an article between said opposed notches, substantially as set forth.

4. A halter fastener comprising a bar having a notch in its face, a body member shaped to fit over the bar and having an opening over said notch, a latch pivoted at one end of said opening, opposed notches in

said latch and said body member, said latch being adapted to be swung into engagement with said body member to clamp an article between said opposed notches, and fastening means for said latch, substantially as set forth.

5. In a halter fastener, a body member having an opening at one face, a latch pivoted at one end of said opening and adapted to be swung into engagement with the body member to clamp an object therebetween and fastening means for said latch comprising a resilient catch adapted to engage the end of the latch, said catch being formed integrally with the body member of the material removed to provide said opening, substantially as set forth.

6. A halter fastener comprising a body member having an intermediate face and side faces extending therefrom, said intermediate face having an opening of a width equal to the width of said face, registering notches in said side faces, a latch pivoted to said body member having notches adapted to be brought into position to clamp a halter in the notches of the body member, and resilient fastening means for said latch, substantially as set forth.

In witness whereof, I have hereunto set my hand and seal at Scout Lake, Saskatchewan, Canada this 22d day of April, A. D. nineteen hundred and twenty-four.

ANDREW OFSTEDAH. [L. S.]
